TAPPET CONSTRUCTION

Joseph H. Hoern and Martin D. Archangeli, Birmingham, Mich., assignors to Eaton Manufacturing Company, Cleveland, Ohio, a corporation of Ohio

Application June 21, 1944, Serial No. 541,410

4 Claims. (Cl. 123—90)

1

This invention relates to internal combustion engines and particularly to valve tappets employed in connection therewith, the principal object being the provision of a valve tappet of minimum weight and in which the distortion thereof under load is so controlled as to minimize if not eliminate the possibility of seizure of the tappet in its guide.

Objects of the invention include the provision of a thin walled generally cylindrical hollow valve tappet so constructed and arranged that when under axial compressive load at least certain areas thereof will tend to contract in diameter, thereby minimizing the tendency of other portions thereof to bulge or expand under such conditions; the provision of a valve tappet of hollow cylindrical construction and of such wall thickness that it would increase in diameter between its ends under load if not prevented, so formed and constructed that the tendency to radially expand under load is reversed over at least certain portions thereof; the provision of a valve tappet as above described which actually decreases in radial dimensions over certain portions thereof under axial load; the provision of a valve tappet of hollow cylindrical construction the walls of which are generally of such thinness that although capable of supporting compressive loads normally met with in service are incapable of so doing without radial expansion unless otherwise prevented, together with means cooperating with such walls tending to reverse the tendency of radial expansion over certain areas thereof under such compressive forces as are met with in service; the provision of a valve tappet as above described in which such means for reversing the tendency towards radial enlargement consists of a bead or rib integral with the walls of the tappet intermediate the ends thereof and extending circumferentially about the interior of the tappet; the provision of a valve tappet as above described in which the internal rib is of such size as to effect an actual radial contraction of the walls of the tappet over and adjacent to the axial length of such rib under the conditions stated; and the provision of a valve tappet as above described in which the rib is positioned at that point in the length of the tappet which would radially enlarge to the greatest extent under a compressive load in the absence of such rib.

Further objects of the invention include the provision of an internal combustion engine having a valve, a cam and an operative connection between the valve and cam including a relatively elongated valve tappet having a generally cy-

2

lindrical body guided in a complementary bore of the engine, and spring means constantly urging the valve toward closed position, the tappet being hollow and having walls of such thickness that when otherwise unrestrained would bulge under the load imposed thereon in the opening of the valve against the force of said spring means and in overcoming the inertia of the valve, resulting in binding of the tappet in its bore, together with an internal circumferential rib in the tappet formed integrally with the inner walls thereof and of such size and so positioned as to reverse the tendency of the tappet to expand in the immediate area of the rib and to such extent as to substantially if not completely offset the binding effects of the tappet in the bore under load which would otherwise occur.

The above being among the objects of the present invention, the same consists in certain novel features of construction and combinations of parts to be hereinafter described with reference to the accompanying drawing, and then claimed, having the above and other objects in view.

In the accompanying drawing which illustrates a suitable embodiment of the present invention and in which like numerals refer to like parts throughout the several different views,

Fig. 1 is a partially broken, partially sectioned view taken through an internal combustion engine provided with a valve tappet constructed in accordance with the present invention;

Fig. 2 is an enlarged sectional view taken axially through the body of the tappet shown in the engine of Fig. 1, illustrating in exaggerated form and by dotted lines the relative expansion and contraction of different portions thereof in service;

Fig. 3 is a view of a tappet substantially identical to that shown in Fig. 2 with the exception of the internal rib of the present invention which is not present, and illustrating by dotted lines and in exaggerated form or extent the manner in which it would radially expand under compressive load in service;

Fig. 4 is a view similar to Fig. 2 but illustrating the tappet in an initial stage of construction and illustrating the manner in which the internal rib is formed therein; and,

Fig. 5 is a view similar to Fig. 2 but illustrating a tappet of relatively greater length as compared to its diameter and the use of a plurality of internal ribs to offset the radial expansion thereof under compressive forces met with in service.

It is a generally accepted fact that the most desirable engine for aircraft use is that one de-

livering the greatest horsepower per pound of weight of the engine, providing the engine is capable of operating for a reasonable length of time without undue danger of failure of its operating parts. The energies of substantially all airplane engine designers are directed to this end at the present time. There are two methods by means of which such ideals may be approached, one of which is by increasing the efficiency and, therefore, the power of an engine of particular size, without increasing the weight thereof, and the other one of which is the reduction of the weight of the operating parts of the engine itself without reducing its power. The present invention has to do with the latter types of endeavor. In other words, its object is to reduce the weight of an operating part of the engine without endangering failure of the engine because of some structural or other defect resulting therefrom and, therefore, to provide such part which will be of lighter weight than those heretofore employed for the same purpose, that will operate equally if not more efficiently and without danger of causing failure of the engine either because of breakage of or damage to such part itself, or parts with which it is operatively associated. The particular parts of the engine to which the present invention specifically relates are the valve tappets therefor.

In present day airplane engines valve tappets are necessarily made of a material length and of a material diameter in order to provide sufficient bearing area between themselves and their guides to withstand the movement and forces to which they are subjected in operation. For this reason they are usually made hollow in order to reduce the weight thereof. The greatest saving in weight in such tappets is obviously capable of being obtained by reducing the wall thickness thereof, but before the present invention the reduction in such wall thickness has been definitely limited by reason of the fact that where the wall thickness has been reduced beyond a certain extent, while it is of sufficient thickness, with a reasonable factor of safety, to take the axial compressive load applied to it in service during the opening of a valve without crushing axially, nevertheless the body of the tappet expands under such compressive forces to such an extent as to cause the tappet body to bind in its guide, or at least expand to such an extent as to restrict the amount of lubricant between it and the guide sufficiently to cause scoring of the walls of the tappet or guide and consequent seizure of the tappet in the guide. The problem, therefore, at the time of the conception of the present invention had not been solved to a satisfactory extent inasmuch as the walls of such tappets were still considered to be of a thickness greater than that required to carry the loads to which they were subjected.

In accordance with the present invention it has been discovered that such tappets may be made of a wall thickness or, better stated, thinness, that were it not for the feature of the present invention the tappets would be commercially impractical because they would radially expand under load to such an extent as to present a serious problem of seizure in their guides during operation.

In accordance with the present invention such radial expansion is minimized to such an extent as to render it no longer a problem by forming one or more circumferential ribs integral with the thin walls of the tappet body interiorly thereof. It has been found that by the use of such rib or ribs judiciously located on the interior of

the tappet body and preferably at the point or points where maximum radial expansion thereof would occur under load when not so provided, the tendency of the thin walled tappet body to 5 radially expand under compression over the axial length and adjacent areas of such rib or ribs is reversed, and instead of expanding under load such portions may actually contract under load and in contracting minimize the radial expansive 10 movements of those wall portions of the tappet immediately proximate thereto.

The ribs thus provided in accordance with the present invention are not required to be of great axial or radial dimensions as compared to the 15 overall axial and radial dimensions of the tappet. In fact such ribs are not required to be of substantially greater radial dimensions than the wall thickness required in a tappet body which, when not provided with such ribs, will not radially 20 expand under load beyond safely permissible limits. The result is that by the practices of the present invention the weight of such tappets may be materially reduced without otherwise affecting the desired operating characteristics of the tappet.

It will be appreciated, of course, that although the remarks given above are particularly directed to the importance of the present invention in connection with the tappets for aircraft engines, 30 the reduction in weight of operating parts including tappets in all types of engines is usually recognized as desirable, and equivalent reduction in weight may be realized by the application of the present invention to other types of engines even 35 though in such cases the reduction in weight may not be of as great importance. It will also be appreciated that the tappet of the present invention is adaptable for use in various types of engines having various forms of valve mechanisms, 40 that shown in Fig. 1 being simply illustrative of the application of the invention to one type of engine having one type of valve operating mechanism and simply for the purpose of illustration and not limitation.

45 The engine shown in Fig. 1 will be seen to include a crankcase 10 having a cylinder block 12 in which is received a cylinder liner 14 in which a piston 16 is reciprocably received in a conventional manner. A conventional crankshaft 18 is 50 rotatably supported in the crankcase 10 by suitable bearings such as 20 and is conventionally connected by a connecting rod 22 with the piston 16 in the cylinder liner 14. The cylinder block 12 is provided with a valve port 24 communicating 55 with an intake or an exhaust passage 26 with the space above the piston 16 in the cylinder liner 14, a valve 28 serving to control the opening and closing of the port 24. The valve 28 is guided in its reciprocable movements by a valve guide 30 and spring means indicated generally at 32 cooperate with the valve 28 in a conventional manner to constantly urge it towards closed position. The valve 28 is opened against the force of the spring means 32 by means of a rocker arm 34 pivotally 60 mounted on the cylinder block as at 36. The rocker arm 34 is operated from the crankshaft 18 by means of a cam 38 concentric with the crankshaft 18 and driven therefrom and acting through a valve tappet indicated in Fig. 1 generally at 40 and a push rod 42. The valve tappet 40 is guided in its reciprocating movements in the bore of a tappet guide 44 carried by a member 46 suitably and rigidly fixed to the crankcase 10 and/or cylinder block 12.

Although the present invention is adaptable to

any of the various forms of tappets having hollow cylindrical bodies, by way of illustration the particular tappet 40 shown comprises a main body portion indicated generally at 50, the lower end of which is bifurcated as at 52 and within which is received a roller 54 which rides upon the periphery of the cam 38, the roller 54 being rotatably mounted in the bifurcated lower end of the main body portion by means of a pin 56 preferably pressed fitted in a bore 58 extending transversely through the legs of the bifurcated lower end of the main body portion 50. The major portion of the main body portion 50 is hollow and open at its upper end which is closed by a shouldered plug 60 received therein and the shoulder of which seats upon the upper end of the main body portion 50. The plug 60 is provided with a partially spherical seat 62 therein in which the lower ball end of the push rod 42 is received. The hollow walls of the main body portion 50 are imperforate except for one or more relatively small holes 64 provided therethrough adjacent the lower end of the hollow interior of the main body portion 50 and which hole or holes are adapted to be intermittently aligned during operation with an oil passage 66 leading to the bore of the tappet guide 44 and connected as by means of a tube 68 with the pressure lubricating system of the engine. The oil thus led to the interior of the tappet is discharged upwardly through a central hole in the plug 60 and into the interior of the push rod, from which it is carried to the bearing for the rocker arm 34. The oil in the passage 66 in being fed to the bore of the guide 44 serves to lubricate the wearing surfaces between the guide and the tappet 40.

The main body portion 50 of the valve tappet 40 is illustrated in greater detail in Fig. 2 and it will be understood that it is the character of the hollow walls thereof that constitutes the gist of the present invention. As indicated in Fig. 2 the bore 70 extends from the upper end of the main body portion 50 to a point immediately above the bifurcation 52 in the lower end thereof where such bifurcation is employed, otherwise into a similar relation with the cam contacting face of such end of the main body portion where the tappet is formed for direct engagement with an operating cam and without the inter-position of a roller such as 54. Preferably and as indicated in Fig. 2 the substantially imperforate walls of the hollow portion of the main body portion 52 are thickened as at 72 adjacent the open end of the tappet so as to better prepare it for reception of the plug 60 or the equivalent for transmitting the load therefrom with less liability of deformation or the like of such end. It will be appreciated that the walls of the hollow portion of the tappet body 50 are unusually thin as compared to the wall thicknesses of similar constructions employed in conventional practice. For instance, in a tappet having such thin wall portion approximately $2\frac{5}{8}$ " long and an external diameter of $\frac{13}{16}$ of an inch the wall thickness may be on the order of $\frac{1}{32}$ of an inch. This size of tappet conforms in external dimensions to those now conventionally employed in conventional types of large radial engines now being produced in great quantities for aircraft use, but in which tappets a wall thickness of substantially twice or more than that indicated is conventionally being employed.

In accordance with the present invention an internal rib or bead 74 is formed integrally with the thin walls of the body 50 and preferably but

not necessarily midway between the thickened upper end 72 and the closed lower end thereof. Preferably it is midway the length of the thin walled portion where the length of the thin walled portion is such that one such rib will suffice. The rib or bead 74 is circumferentially unbroken and its cross-sectional configuration and axial extent is not important. In other words, its axial extent may be approximately as small as its radial dimension, or on the other hand, it may gradually taper from a high point at its axial midpoint, equally or unequally, in opposite directions to point or points adjacent the ends of the thin walled portion. In the particular case shown its cross-sectional configuration approximately conforms to parts of a segment of a circle and it is approximately fifteen times as long as it is thick, this being by way of illustration illustrating one form and size of rib or bead which has proven successful in tappets of the size stated and subjected to the loads met with in engines of the type referred to. The radial thickness of the rib or bead 74 in the particular example shown is substantially equal to the wall thickness of the thin walled portion of the main body portion 50.

Referring now to Fig. 3 a tappet body is shown in which the various parts thereof are indicated by the same numerals as in Fig. 2 except that such numerals bear a prime mark. The tappet shown in Fig. 3 is identical to that shown in Fig. 2 with the exception that the rib 74 is eliminated, the thin side walls being of uniform thickness from end-to-end. When the tappet shown in Fig. 3 is subjected to the load conventionally met with in an engine of the size and type described, when the maximum compressive load is applied to it the side walls expand as indicated in greatly exaggerated form by the dotted lines 80, such expansion following Poisson's ratio and in amounts up to 0.0007". Inasmuch as these tappets are fitted in their guides in actual practice as close as possible and still permit a running fit, normally requiring a clearance between the tappet and its guide of 0.0005" or less, it will be appreciated that under such conditions the valve tappet body shown in Fig. 3 will expand to such an extent in service as to take up all clearance between it and the guide, eliminating the lubricant to a great extent and in a relatively short time causing a seizure between the tappet and its guide. On the other hand, by the employment of a rib such as the rib 74 in Fig. 2 this expansion under load can be completely or substantially completely eliminated so that even in spite of the equivalently thin walls and identical loads the valve tappet body illustrated in Fig. 2 will maintain a desired, or at least a workable, degree of clearance between it and the walls of its guide.

Theoretically the deformation of the valve body shown in Fig. 2 will include an expansion of it as indicated in greatly exaggerated form by the dotted lines 82 between the rib 74 and the opposite end portions of the tappet body 50, and a radial contraction, indicated in greatly exaggerated form by the dotted line 84 connecting the dotted lines 82, over the axial length of the rib 74 and portions of the thin walls immediately adjacent thereto. In actual practice, however, no substantial increase in the diameter of the body of the tappet between the ribs 74 and the opposite ends of the tappet has been observed, but the central portion over the axial length of the rib 74 has shown a decrease in diameter of 0.0003" under the same loads as have caused an expansion of 0.0007" with the construction illustrated in Fig. 3.

Obviously, by changing the radial thickness of the rib 74 the amount of contraction of the equivalent axial portion of the tappet body may be equivalently varied so that almost any desired condition of deformation under load may be obtained. Ordinarily it will be desirable to make the ribs 74 of such radial thickness as to maintain the major areas of the thin walled portion of the tube against substantial increase in radial dimensions under load and so as to, in effect, maintain such major areas at substantially the same diameter as that determined for the proper clearance for the tappet in its cooperating guide when the tappet body is in free and unstressed condition. This is for the reason that under such circumstances the fit of the tappet body in the guide will be constant under all conditions, that is whether it is under load or not. The small axial length of the tappet body under such conditions which will decrease in external dimensions will not be large enough to materially detract from the desired area of contact between the tappet body and its guide and will, therefore, not materially affect the wear characteristics of the tappet in the guide.

The term "thin walled" has heretofore been employed to designate a characteristic of the valve tappet of the present invention and the only specific example given has been a tappet having such thin walls of certain length and diameter and of approximately $\frac{1}{2}$ of an inch in thickness. It will be appreciated, however, that the term "thin walled" is a relative term and what may be thin walled in one construction may not be so considered in another, depending upon the relative length of the thin walled section as compared to its diameter, the maximum load which the tappet is required to transmit through it, the material from which the tappet is made and its condition of hardness, etc. The term "thin wall" as herein employed is intended to mean a wall of such thickness that under the maximum loads which it is designed to carry in service the thin walled portion of the tappet body would radially expand to such a degree as to take up substantially all or most of the clearance intended to exist between it and the wall of the cooperating guide and thereby endanger sticking of the tappet body in the guide, were it not for the presence of the internal rib or ribs of the present invention. Although the internal rib or ribs of the present invention may be provided in the bore of the tappet body in any suitable or conventional manner the method of forming them illustrated in Fig. 4 is preferred particularly in view of the fact that the internal surfaces of the main body portions of such tappets should be of a smooth and polished nature, which effect would be difficult to obtain if it were attempted to machine the ribs directly in the bore of the tappet body. According to the method disclosed in Fig. 4 and which illustrates the method of forming the tappet body illustrated in Fig. 2, a blank is first formed of slightly greater length than the desired length of the finished body. This blank is of circular section and generally of a diameter as illustrated at 88 sufficiently larger than the diameter of the desired finished body to provide sufficient stock for the later machining operations. It is provided with a bore 88 of constant diameter throughout, equal in diameter to the maximum diameter desired in the bore of the finished product, and of a length equivalent to the bore 70 desired in the finished tappet. The bore 88 is preferably brought to a condition of relatively high or fine finish, this being readily possible because of the

fact that it is fully cylindrical and is not obstructed by any rib such as the rib 74 or any constriction such as is provided by the thickened upper portion 72 in the final product. The lower end of the blank shown in Fig. 4 may be substantially identical to the size and shape of the lower end of the finished tappet except that it need not be bifurcated nor provided with the cross-hole 58 as will occur in the final product, these features preferably being added later.

In the axial length of the blank in Fig. 4 corresponding with the position of the rib 74 in the final product, the blank is externally provided with a circumferentially extending rib or bead 90 which is of a cross-sectional area substantially equal to the cross-sectional area of the bead 74 in the final product. Its cross-sectional contour may be varied to obtain any desired cross-sectional configuration of the bead 74 in the final product as will be readily appreciated. At its upper end the blank shown in Fig. 4 is provided with an increased wall thickness providing a radially outwardly projecting integral collar portion 92 thereon, the same being of substantially the same or substantially greater cross-sectional area as the thickened end 72 desired in the final product.

The lower solid end of the blank shown in Fig. 4 and above described is inserted into a ring die 94, a plunger such as 96 is inserted into the bore 88 and against the solid bottom wall thereof, and a relative force is exerted between the plunger 96 and the ring die 94 to force the blank through the ring die 94. Inasmuch as the bore 98 in the ring die 94 is substantially the same as the diameter 86 of the blank, in pushing the blank through the ring die the bead or rib 90 is displaced radially inwardly until it is located in the plane of the walls of the body and an equivalent amount of metal is projected radially inwardly of the bore 88 to form the rib 74 in the final product. Likewise that portion of the thickened end 92 of the blank which is located outwardly of the diameter 86 is forced inwardly until its outer diameter is the same as the diameter 86, and the metal on the inner side thereof is displaced radially inwardly into the bore 88 to form the thickened end wall portion 72 of the final product. Inasmuch as the walls of the bore 88 were in smooth and polished condition before the last-mentioned operations, it will be appreciated that the walls of the bore 70, including the inner surfaces of the rib 74 and the thickened end wall portion 72, will be correspondingly smooth and polished in the final product.

After the last-mentioned operation it will usually be desirable to re-machine the internal surface of the thickened end 72 to insure its correct size and concentricity with the axis of the tappet body, the slot 52 and cross-hole 58 will be machined therein, together with the holes 64, the whole then preferably being hardened and the external surfaces ground to final shape and size.

As previously mentioned the relative length of the thin walled portion of the tappet body such as that described as compared to its diameter is a factor in the amount of radial expansion which will occur upon a given axial compressive load being applied to the tappet body, the greater the relative length as compared to the diameter the greater the amount of radial expansion. In such cases it may be necessary to employ two or more internal ribs such as the ribs 74 heretofore described in order to properly control the thin

walls against undue radial expansion. Such construction is illustrated in Fig. 5 which is identical to the construction illustrated in Fig. 2 except for the relative length as compared to the diameter. Inasmuch as this is the only change from the prior construction, equivalent parts therein are indicated by the same numerals as in Fig. 2 except that such numerals bear a double prime mark. In this case it will be noted that two ribs 74'' are employed, these being so positioned with respect to each other and the length of the thin walled portion of the tappet body as to be substantially equally spaced from each other and from the corresponding heavier end portions of the tappet body. In this case the two ribs have the effect of breaking up the length of the thin walled portion of the tappet body 50'' into three relatively short sections, whereas in the previously described construction the rib 74 broke up the corresponding length of the body 50 into two such sections. Any desired number of ribs may, of course, be employed but it is, of course, desirable to use the minimum number capable of accomplishing desired results inasmuch as under such circumstances a tappet body of minimum weight will be provided.

One thing to be noted in connection with the present invention is that the rib or ribs 74 provided in accordance with the present invention are not reinforcing ribs in any sense as they have little if any function in this respect. Their function is to provide a center of mass located radially inwardly of the center of mass of the thin side walls per se which under the force of compression applied to the tappet will cause that and adjacent areas of the thin walls to minimize and preferably reverse its tendency toward radial outward expansion which would otherwise occur, and even prevent or actually reverse such outward expanding of the thin walls and effect an actual radial contraction thereof if desired. As previously stated, the thin walls without such rib or ribs are themselves capable of taking the compression loads to which they are subjected in service without permanent deformation but not without temporary deformation, so they do not require such ribs for reinforcing purposes. The ribs are provided for controlling the temporary distortion which occurs under such circumstances.

Having thus described our invention, what we claim by Letters Patent is:

1. A hollow tappet body of circular cross-sectional configuration having substantially imperforate thin side walls of such thickness that unless otherwise prevented such thin side walls will radially expand, without permanent deformation, under the compressive loads to which it is subjected in service, and a circumferentially unbroken rib integral with said side wall on the interior thereof and intermediate the ends of said side wall, said rib being axially elongated and of a length relatively greater than either its radial thickness or thickness of the wall of the tappet body whereby to reverse the tendency of said side wall, over the axial length of said rib, to radially expand under said compressive loads in service.

2. A valve tappet including a body of circular cross-sectional configuration and including a portion having a substantially circumferentially

unbroken wall of such thickness that unless otherwise prevented it will expand, without permanent deformation, under the compressive loads to which it is subjected in service, and a rib formed integrally with the inner surfaces of said walls and projecting radially inwardly therefrom in circumferentially unbroken condition intermediate the ends of said walls, the radial dimension of said wall and rib combined being substantially no greater than the thickness of the corresponding wall of a tappet of the same size and material but of constant and sufficient wall thickness to withstand said loads in service without material deformation, and said rib having an axial length materially greater than the thickness of either the rib or wall whereby to reverse the tendency of said wall at and adjacent said rib to radially expand under said loads.

3. In a tappet, in combination, a hollow main body portion having a substantially unbroken wall portion bounded at each axial end thereof with more rigid wall portions, the first-mentioned wall portion being of such thickness that unless otherwise prevented it will radially expand under the compressive loads to which said tappet is subjected in service to an undesirable extent but without permanent deformation, and a circumferentially unbroken rib extending circumferentially around the bore of said tappet intermediate the ends of said first-mentioned wall portion and formed integrally with said first-mentioned wall portion, said rib being of greater length than the thickness of either the rib or wall whereby to effect a reduction in the diameter of said wall portion over at least the axial length of said rib under the maximum value of said loads.

4. In a tappet, in combination, a hollow main body portion having a substantially unbroken wall portion bounded at each axial end thereof with more rigid wall portions, the first-mentioned wall portion being relatively long as compared to its diameter and being of such thickness that unless otherwise prevented it will radially expand under the compressive loads to which said tappet is subjected in service to an undesirable extent but without permanent deformation, and a plurality of axially spaced ribs in the bore of said body portion intermediate the ends thereof extending in circumferentially unbroken relation about said bore and formed integrally with the inner surface of said first-mentioned wall portion, each of said ribs being of a length relatively greater than its radial thickness.
